UNITED STATES PATENT OFFICE.

JOHN LINES, OF WATERBURY, CONNECTICUT, ASSIGNOR TO THE SCOVILL MANUFACTURING COMPANY, OF SAME PLACE.

DESIGN FOR A COIN-HOLDER.

SPECIFICATION forming part of Design No. 22,216, dated February 14, 1893.

Application filed November 21, 1892. Serial No. 452,731. Term of patent 7 years.

To all whom it may concern:

Be it known that I, JOHN LINES, of Waterbury, in the county of New Haven and State of Connecticut, have invented a new Design 5 for a Coin-Holder; and I do hereby declare the following, when taken in connection with accompanying drawing and the letters of reference marked thereon, to be a full, clear, and exact description of the same, and which 10 said drawing constitutes part of this specification, and represents a perspective view of a coin-holder containing my design.

This invention relates to a design for that 15 class of coin-holders which are adapted to be carried in the pocket, and consists in a circular box having its periphery ornamented with vertical and horizontal lines so as to give the box the appearance of a pile of coins.

The coin-holder containing my design, consists of a small circular box, closed at its upper end by a disk of slightly smaller diameter, and also provided at its upper end with 20 a segmental flange extending inward over the

said disk, corresponding to the external diameter of the box, and containing a few more 25 degrees than one hundred and eighty degrees of a circle, or, in other words, being a little more than semi-circular. The edge of the said box is encircled by straight vertical lines placed close together, and by horizontal lines 30 of wider separation from each other, whereby the box is given the appearance of being a pile of coins, the straight vertical lines forming the milled edges of the coins represented, and the horizontal lines seeming to separate 35 the same.

I claim—

The design for a pocket coin-holder as herein shown and described.

In testimony whereof I have signed this 40 specification in the presence of two subscribing witnesses.

JOHN LINES.
